UNITED STATES PATENT OFFICE

95,158

DESIGN FOR A TREAD PLATE

Victor M. Surerus, Chicago, Ill., assignor to In-
land Steel Company, Chicago, Ill., a corpora-
tion of Delaware

Application December 7, 1933, Serial No. 49,986

Term of patent 14 years

To all whom it may concern:

Be it known that I, Victor M. Surerus, a citizen of the United States, residing at Chicago, county of Cook, and State of Illinois, have invented a new, original, and ornamental Design for a Tread Plate, of which the following is a specification, reference being had to the accompanying drawing, in which—

Fig. 1 is a plan view of the tread-plate, showing my new design, and Fig. 2, an enlarged broken sectional view taken at the irregular line 2 on Fig. 1 and viewed in the direction of the arrow.

I claim:

The ornamental design for a tread plate substantially as shown and described.

VICTOR M. Surerus.
